Primary Examiner—Daniel D Bui

(74) *Attorney, Agent, or Firm*—Taylor & Aust, P.C.

(**) Term: **14 Years**

(57) **CLAIM**

(21) Appl. No.: **29/342,417**

The ornamental design for a keying configuration for an electrical connector, as shown and described.

(22) Filed: **Aug. 25, 2009**

DESCRIPTION

(51) **LOC (9) Cl.** 13-03

FIG. 1 is a perspective view of a keying configuration for an electrical connector showing my new design;

(52) **U.S. Cl.** **D13/154**

FIG. 2 is a front view thereof;

(58) **Field of Classification Search** D13/133,

FIG. 3 is a side view thereof, the opposite side view being substantially identical;

D13/146-147, 153, 154, 184; 439/266, 345,

FIG. 4 is a side view thereof, the opposite side being a mirror image thereto; and,

439/350, 352, 357-358, 476.1, 595, 660,

FIG. 5 is a bottom view thereof.

439/680, 752

See application file for complete search history.

The broken line portion of the figure drawings is included to show unclaimed subject matter only and forms no part of the claimed design.
